CLAIM

The ornamental design for the telephone booth, as shown and described.

DESCRIPTION

FIG. 1 is a perspective view of a telephone booth, showing my new design; the broken lines showing of environment is for illustrative purposes only and form no part of the claimed design;

FIG. 2 is a front elevational view thereof;

FIG. 3 is a right side elevational view, the left side being a mirror image thereof;

FIG. 4 is a top plan view thereof;

FIG. 5 is a bottom plan view thereof; and

FIG. 6 is a rear elevational view thereof.
